UNITED STATES PATENT OFFICE.

AUBREY AUGUSTUS BROOKS, OF TORONTO, ONTARIO, CANADA.

LEG AND ANKLE SUPPORT.

Application filed October 27, 1923. Serial No. 671,235.

The principal object of the invention is to provide a support for the ankle and leg which will effectively brace the limb against unaccustomed or abnormal strains but which 5 will allow perfect freedom of movement, thus enabling persons having weak ankles enjoying the pleasures of active outdoor exercise.

A further object is to provide a light, 10 strong support which may be easily and quickly attached and removed and which is instantaneously adjustable to fit the wearer.

A still further object is to provide a device which will guard the ankles of the 15 wearer from external injury.

The principal feature of the invention consists in providing a stirrup member to extend beneath and embrace the foot and pivotally connecting same to an adjustable rigid 20 bracing member adapted to be secured to the leg.

In the drawings, Figure 1 is a perspective view showing a pair of the supporting devices attached to the wearer.

25 Figure 2 is a front elevational part sectional view of one of the supporting devices.

Figure 3 is a perspective detail of the stirrup member which embraces the underside of the foot and to which the lower ends of 30 the brace rods are pivotally secured.

Figure 4 is a perspective view of the leg strap and brace rods from which the stirrup has been removed.

Ankle supports of various forms have 35 been devised with a view to overcoming the undesirable effects of weak ankles and the present invention contemplates a considerable improvement on those heretofore in use since it not only supports the ankle in a highly effective yet non-restrictive manner, but is so constructed as to not bind or 40 restrict the action of the leg muscles or interfere with blood circulation.

In the structure shown the foot stirrup is 45 formed of a plate 1 having upwardly projecting side plates 2 adapted to fit snugly into the side arches of the shoe, the plate portion 1 extending under the instep and engaging the forward part of the heel. The 50 plate 1 if desired may be formed in a cup shape to fit over the heel of the shoe, the object being to have the member 1 engage the foot with a firm grip.

Secured to the under side of the plate 1 is 55 a transversely arranged bearing here shown in the form of a tubular member 3 which is

held rigidly in place by means of the metal straps 4 which are riveted to the plate 1.

A rigid rod 5 having a laterally bent end 6 is journaled in the bearing 3 and extends 60 upwardly alongside the inward side of the leg. A rigid rod 7 provided with an eye 8 at the end fits over the threaded end 9 of the rod 5 projecting beyond the journal 3 and extends upwardly on the outer side of 65 the leg substantially parallel with the rod 5. The rod 7 is secured to the end of the rod 5 by a suitable nut 10.

The rods 5 and 7 extend upwardly from 70 the member 1 and slidably arranged thereover are a pair of tubular members 11 and 12 which extend upwardly and are flattened at their upper ends and curved arc-shaped plates 13 are securely riveted thereto.

Suitable loops 14 project outwardly from 75 the plates 13 through which the leg-encircling strap 16 is threaded.

To secure the device in place the stirrup is first placed under the instep of the foot. 80 The members 11 and 12 are then drawn upwardly until the plates 13 fit into the hollow above the calf of the leg and the strap 16 is buckled snugly around the leg. The telescopic rods thus form a rigid support from a point just below the knee to the bottom of 85 the foot and it will be impossible to turn the ankle.

At any time when it is desired to remove 90 the supporting device from the shoe to facilitate carrying or for other purposes this may be very quickly and easily accomplished by simply unthreading the thumb nut 10 and thus removing the telescopic members from their connection with the shoe.

A device such as described is extremely 95 simple yet highly efficient in the results it accomplishes. The pivot connection between the braces and the stirrup allows perfect freedom of heel and toe action and the tubular members slip freely on the rods and prevent any binding or cramping of the foot action.

Wear on the sides of the shoes by the 100 pivotal movement of the braces is prevented by the side shields of the stirrup.

The device is shown as applied in skating but its use is however not limited to skating but it may be used equally beneficial as a protection for the ankle and leg when the wearer is engaged in other sports wherein the ankle or limbs are liable to be subject to abnormal strains or injury.

What I claim as my invention is:—

1. A leg and ankle support, comprising, a stirrup member extending beneath and securely embracing the foot, and telescopic brace members pivotally connected to said stirrup and extending upwardly past the sides thereof and secured to the leg.
2. A leg and ankle support, comprising a stirrup member extending beneath and securely embracing the foot and having a journal extending therebelow, a pair of rods pivoted in said journal and extending upwardly either side of the foot, a pair of rods telescoping the aforesaid rods, and means for securing the upper ends of the latter rods to the leg.
3. A leg and ankle support, comprising in combination with a shoe, a pair of rods arranged one on each side of the shoe, means for pivotally connecting said rods to the shoe, a tubular member telescopically arranged on each of said rods and extending

upwardly therefrom beyond the ends thereof, and means for securing the upper ends of said tubular members to the leg.

25

4. A leg and ankle support, comprising in combination with a shoe, a plate adapted to extend beneath the shoe and to engage it on either side, a bearing carried by said plate and extending transversely thereof, an adjustable rod having one end extending through said bearing and projecting a short distance therebeyond and having the other end bent upwardly, an adjustable rod having an eye at its lower end to receive the projecting portion of the former rod, a nut threaded on the end of said projecting portion to secure the eye rod in place, and means arranged on the upper ends of said adjustable rods adapted to be firmly held in position on the leg.

In testimony whereof I have hereunto set my hand.

AUBREY AUGUSTUS BROOKS. [L.S.]
